G. H. CURTISS.
AIRPLANE LANDING GEAR.
APPLICATION FILED MAY 13, 1918.

1,392,272.

Patented Sept. 27, 1921.

FIG. 1.

FIG. 2.

Inventor

GLENN H. CURTISS.

By his Attorney

John P. Harboe

UNITED STATES PATENT OFFICE.

GLENN H. CURTISS, OF GARDEN CITY, NEW YORK, ASSIGNOR TO CURTISS AEROPLANE AND MOTOR CORPORATION, A CORPORATION OF NEW YORK.

AIRPLANE LANDING-GEAR.

1,392,272.

Specification of Letters Patent. Patented Sept. 27, 1921.

Original application filed August 22, 1911, Serial No. 645,340. Divided and this application filed May 13, 1918. Serial No. 234,250.

To all whom it may concern:

Be it known that I, GLENN H. CURTISS, a citizen of the United States, residing at Garden City, in the county of Nassau and 5 State of New York, have invented certain new and useful Improvements in Airplane Landing-Gears, of which the following is a specification.

My invention relates to heavier than air 10 flying machines and has reference more particularly to such improvements in landing gear construction as are described and illustrated in an application filed by me December 6, 1916, Serial Number 145,402, which application is in turn a division of an application filed August 22, 1911, Serial Number 645,340.

The landing gear is characterized by an 20 arrangement of struts in pairs, the struts, in each instance being V-arranged with their apices founded upon a supporting base of the flotation type. The particular location of these struts with respect to the wing structure and with respect to the motor 25 mass, will be hereinafter pointed out. It is sufficient to state that the arrangement of the struts is such that maximum strength is provided with a minimum of resistance to the air. Moreover, special consideration 30 has been given the arrangement of the struts with a view to effectually distributing the hydroplaning and landing impacts which are more or less severe and racking in hydro-aero machines.

35 While the features above generally referred to have been illustrated in connection with what is now known as a hydro-airplane, it is to be understood that no limitation whatsoever to this particular type of 40 craft is intended. The V-arrangement of struts is equally as well adaptable to land machines.

Of the drawings:

Figure 1 is a perspective view from the 45 front, parts having been omitted in order not to complicate the drawings; and

Fig. 2 is a side elevation.

As intimated, many features of the complete machine have already been described 50 and claimed in applications now pending and will, for this reason, be touched upon but lightly or generally herein. The craft illustrated is of the biplane hydro-airplane type. Supporting surfaces designated respectively

10 and 11 extend transversely across the main 55 flotation body 12 in lifting relation. These surfaces are interconnected and braced by wing posts 13 and cross arranged wires 14. Outriggers 15, arranged in pairs, extend rearwardly from the engine section or mid 60 section of the wing structure. They support at their rearward extremity the directional control surfaces or empennage which 65 comprises elevator flaps 17, a rudder 18 and a horizontal stabilizer 19. The function 70 of these surfaces is obvious. Lateral balance of the craft is obtained by manipulation of ailerons 19' located respectively at opposite sides of its fore and aft axis, preferably intermediate the supporting surfaces 10 and 75 11. The above features of construction, and numerous other features which have been illustrated, form no part of the present invention and will, for this reason, be given little or no consideration hereinafter.

Upon reference to Fig. 1 it will be noted 75 that all chassis or landing gear struts are V-arranged with the apices of the respective V-struts founded upon the top surface of the main flotation body 12. These struts, 80 preferably four in number, I have designated as 20. Two of said struts extend substantially vertically from the underneath surface of the lower supporting surface 11, in the plane of the forward wing beam (not shown); to the flotation body 12, and two substantially vertically from the underneath surface of the supporting surface in 85 the plane of the rear wing beam (not shown). The inner leg of each V-strut extends substantially vertically and the outer leg laterally at an angle to effectually brace the trussed wing structure laterally. Said struts 90 20 and braces 21 constitute the mounting for the flotation body 12. The braces 21 extend diagonally forwardly from the underneath surface of the supporting surface 11 adjacent its leading edge to the top surface of the body 12 directly above a point calculated to receive the brunt of the landing and 95 hydroplaning impact. Said braces 21 may be said to diverge rearwardly and upwardly from a point in the longitudinal vertical plane of the center line of the flotation body to points upon the lower supporting surface 11 directly beneath certain of the forward 100 wing posts 13 of the wing structure and as such divergence is more or less marked, it 105

is evident that the entire wing structure is well braced. The V-struts 20, and more particularly the outer legs thereof, additionally brace the wing structure, laterally 5 however, rather than forwardly. The outer legs of the forward V-struts are so positioned relatively to the lower supporting surface 11 as to support it from beneath at the points above mentioned, *i. e.*, at points directly beneath the forward center wing posts 10 13. The outer legs of the rear V-struts, although similarly extended, engage beneath the rear center wing posts rather than the forward center wing posts already mentioned. 15

From the side, the landing gear struts appear to be single vertical struts but this is because of the fact that the struts at opposite sides of the center line of the flotation 20 body lie in the same transverse vertical plane. It is when viewed from the front that the struts 20 appear to be of substantially V-form. The V-arrangement of struts is preferred, and in fact is extremely desirable 25 because of the known strength of V-struts and their special adaptation to craft of this type in which a relatively wide structure (the wing structure) extends transversely across and is supported by a relatively narrow structure (the flotation body 30 12).

While I have described my invention in detail in its present preferred embodiment, it will be obvious to those skilled in the art 35 after understanding my invention, that vari-

ous changes and modifications may be made therein without departing from the spirit or scope thereof, I aim in the appended claims to cover all such modifications and changes.

What is claimed is:

1. A landing gear for aircraft including a plurality of landing gear struts arranged in pairs, one pair of struts being located at one side of the longitudinal vertical plane of the fore and aft axis of the craft and another pair at the opposite side thereof, a flotation base, the pairs of struts in each instance being substantially vertically disposed to support the flotation base at points respectively fore and aft, and the struts in each instance comprising laterally divergent strut legs which extend at an angle to each other. 45 50

2. A landing gear for hydro-aero machines including laterally separate pairs of landing struts, the struts in each instance comprising laterally divergent strut-legs, flotation means carried jointly by the landing struts and so positioned relatively to the machine 55 as to effectually and properly support it upon the water, and landing braces located forwardly of the landing struts and likewise connecting with the flotation means, the landing braces being located respectively 60 65 at opposite sides of the fore and aft axis of the machine.

In testimony whereof I hereunto affix my signature.

GLENN H. CURTISS.
